200,126

CAMERA

George A. Drucker, 321 S. Wabash Ave., Chicago 4, Ill.

Filed Aug. 22, 1963, Ser. No. 76,325

Term of patent 7 years

(Cl. D61—1)

Fig. 1

Fig. 2

Fig. 3

Fig. 4

FIG. 1 is a front isometric view of a camera, showing my new design;

FIG. 2 is a right-side elevational view thereof;

FIG. 3 is a front elevational view thereof; and

FIG. 4 is a left-side elevational view thereof.

The rear of the camera, not shown, is substantially plain and unornamented.

I claim:

The ornamental design for a camera, as shown and described.
